WARREN H. NUTTER, OF ST. LOUIS, MISSOURI.

AUTOMATIC ENGINE-STOP MECHANISM.

1,117,430.

Specification of Letters Patent. Patented Nov. 17, 1914.

Application filed April 6, 1914. Serial No. 829,940.

To all whom it may concern:

Be it known that I, WARREN H. NUTTER, citizen of the United States, residing at St. Louis, State of Missouri, have invented certain new and useful Improvements in Automatic Engine-Stop Mechanism, of which the following is a full, clear, and exact description, reference being had to the accompanying drawings, forming a part hereof.

My invention has relation to improvements in automatic engine-stop mechanism for steam and other fluid-operated engines; and it consists in the novel features of construction more fully set forth in the specification and pointed out in the claims.

In the drawings, Figure 1 is a side elevation of a conventional Corliss engine having my invention applied thereto, parts of the engine being broken away; Fig. 2 is a horizontal section on the zig-zag line 2—2 of Fig. 1; Fig. 3 is an enlarged elevational and sectional detail of the centrifugal spring-controlled tappet carried by the fly wheel; Fig. 4 is an enlarged side elevation of the 25 valve-controlling mechanism forming a part of my invention; Fig. 5 is a horizontal section on the line 5—5 of Fig. 4; Fig. 6 is a longitudinal sectional detail on the line 6—6 of Fig. 5; Fig. 7 is a view similar to one 30 end of that shown in Fig. 5, with the parts in proper engagement to effect stoppage of the engine; Fig. 8 is a cross-section on the line 8—8 of Fig. 5; Fig. 9 is an end view of the sliding clutch member mounted on 35 the rock-shaft carrying the bell-crank to which the valve-reach rods are coupled; Fig. 10 is a face view of the outer clutch member or that directly controlled by the pull-rod responding to the action of the tappet; Fig. 11 is an enlarged representation of the 40 mechanism illustrated at the right-hand end in Fig. 2, with parts broken away; Fig. 12 is a vertical transverse sectional detail on the line 12—12 of Fig. 1; and Figs. 13 and 45 14 are diagrammatic views illustrating the relative positions of the various formations of the several clutches as shown in Figs. 5 and 7 respectively.

The present invention is directed particularly to mechanism for exercising control of the steam-valves and governor of a Corliss engine with a view of cutting off the steam supply to the cylinder should the engine speed up excessively for any reason, as for example owing to excessive slippage or breakage of the governor-belt, although it

must be understood that I do not restrict the invention to this particular type of engine.

The object of the invention is to exercise 60 control over the steam or inlet valves through the agency of devices responding to centrifugal force under conditions of excessive speed of the engine shaft and fly-wheel thereof.

A further object is to construct a stop mechanism which is exceedingly simple, positive, reliable, and one possessing further and other advantages better apparent from a detailed description of the invention, which 70 is as follows:

Referring to the drawings, E, represents the body or frame of a conventional Corliss engine, S, the drive-shaft, W, the fly-wheel, G, the governor, 1, the governor-staff, and 75 2, the governor-shaft. The latter has mounted thereon the pulley 3 from which leads a belt 4 to the shaft S. Secured to the staff 1 is a bracket 5 carrying the cross tubular member or bearing 5' in which is 80 mounted a rock-shaft 6 one end of which carries the balancing lever 7 provided with the usual weight B. Set-screwed to the shaft 6 adjacent the end of the tubular bearing 5' opposite that at which the lever 7 85 is disposed, is a collar 8 forming a male clutch member of a series of clutches to be presently referred to, and through the medium of which the inlet valves are controlled as subsequently to be explained. The member 8 is provided with a lever-arm 9 the outer end of which is pivotally coupled to the lower end of the governor connecting-rod or link 10 whose upper end is secured to the governor cross-head 11 carried by the 90 plunger 12 of the governor. With the exception of the clutch-collar 8, the parts described are well understood in the art and are shown more or less conventionally herein. Mounted loosely on the rock-shaft 6, 100 adjacent the male clutch-member 8 is a female clutch member or collar 13, the said member constituting the hub of the lever-arms 14, 14, from which lead the reach-rods 15, 15, to the cam-levers 16, 16, on the inlet bonnets of the live steam or inlet valves. The wrist-plate 17 is connected by the valve-rods 18, 18, and 19, 19, to the inlet and exhaust valves V, V', respectively, said wrist-plate being actuated from the engine eccentric L through the reach-rod 20, rocker-arm 21, and eccentric-rod 20'. The valves V are 105 110

provided with the steam and safety cams 22, and 23, respectively, as well understood in the art.

As fully understood in the art, when the 5 governor balls attain an excessive rate of speed (as a result of overspeeding of the engine) they fly outwardly and upwardly, thereby reducing the quantity of steam admitted past the inlet valves V into the cylinder C. When the speed of the engine drops below a given point, the governor balls drop, allowing a greater quantity of steam to enter the cylinder. Under my present invention, it is desirable, when the governor-belt 4 10 breaks or slips excessively, (under which conditions the belt-pulley 3 is respectively stopped or reduced in speed, causing the governor balls to lose control of the inlet valves, and to drop to a point where excessive quantities of steam are admitted to the cylinder, thus speeding up the engine to an undesirable degree) that the levers 14, 14, are oscillated in proper direction to close the valves V, and cut off the motor-fluid. 15 This result is attained by the clutches which I shall now describe in detail, and by the centrifugally operated tappet mechanism to which said clutches are responsive. These instrumentalities may be described as follows: Secured to one of the bosses w through 20 which the two sections of the fly-wheel W are bolted together, is a bracket 24 to which is in turn secured in any mechanical manner a hollow arm or tube 25 in which is free 25 to reciprocate a stem 26 terminating in an outer head or tappet h and in an inner head h', the stem operating freely through a screw-cap 27 secured to the free end of the tube 25, a coiled compression spring 28 enclosing 30 the stem and bearing respectively against the head h' and screw-cap 27, normally tending to force the head h' inwardly and thus draw the stem into the tube and bring the head h in proximity to 35 the screw-cap.

With an excessive speed of rotation of the fly-wheel, the centrifugal force will act to drive the stem 26 radially outward (the axis of the member 25 being disposed in a 40 plane parallel to the plane of rotation of the fly-wheel), thereby compressing the spring 28 and projecting the head h some distance beyond the cap 27 (see dotted position in Figs. 2, 3 and 11). As the centrifugal force 45 drops by reason of a reduction in the speed of rotation of the fly-wheel, the spring expands and draws the stem back into the tube 25. The ejection of the stem by the centrifugal force is facilitated by the head h 50 which acts as a weight for the stem. Proper tension may be imposed on the spring 28 by either the screw-cap or by employing a spring originally of the proper tension, so as to respond to any degree of centrifugal force developed. Disposed in the path of

the circular travel of the tappet h when projected outwardly under excessive centrifugal action, is the central stem or tripper arm 29, of a yoke 30 hinged to the outer terminal head or cap-piece 31 of a sleeve or tube 32 coupled to, and forming an extension of, a tube 33, the connection being effected by means of a union 34 whose central perforated wall forms a seat for the inner end of a compression spring 35, the opposite or outer end of the spring bearing against a radial pin 36 on a trigger-rod 37 freely traversing said members 31, 32, 33 and 34 (Fig. 11). One end of the rod 37 is adapted to bear against the base of the yoke 30, and remain in engagement therewith under the resilient action of the controlling spring 35, when the yoke is swung to bring the base thereof opposite and against the end of the rod, the stem 29 being then substantially coincident with the axis of said rod. The tube 33 is rigidly supported from the top of a standard 38, the opposite and thicker end 37' of the rod projecting a slight distance beyond the standard (the part 37' being made thicker than and forming an offset with, the part 37, said offset serving to arrest the rod in its outward throw in the tube 33 which is bored to conform to the parts 37, 37'). The projecting end 37' is adapted to 50 be brought into engagement with the upturned arm or finger a of a second inclined trigger-rod 39 mounted loosely in a tube 40 which is rigidly secured to a T 41 at the upper end of a tubular angle-bracket 42 leading from the standard 38, the rod 39 traversing the T and the central perforated wall thereof, as well as the tubular bearing 40' coupled to the T on the opposite side of said wall. (Fig. 11.) The upper end of 55 the rod 39 is coupled to the arm 43 of a third clutch-member or collar 44 mounted loosely on the rock-shaft 6, and to which further reference will hereinafter be made. The trigger-rod 39 is controlled by a compression-ejecting spring 45 within the guide tube 40, one end of the spring bearing against the central partition of the T 41, the opposite end engaging a pin 46 on the rod. A collar 47 set-screwed to the shaft 6 prevents the clutch 44 from slipping off the shaft (Figs. 5, 7). 60 The member 8 serves as a male clutch member for the female clutch-member 13, the latter in turn serving as a male for the 65 female member 44. One end of the member 8 is provided with projections or processes d which are adapted to enter corresponding depressions or recesses e in the member 13, the said projections being free to traverse 70 the face m between the depressions during certain portions of the arcuate travel of said projections as presently to be more fully described, the two members 8 and 13 being provided with adjacent sockets i, i, jointly form- 75

ing a chamber or housing for a compression spring 48, which, under conditions to be presently described forces the members apart (Fig. 7), that is to say, it causes the processes or projections d' , d' , of the member 13 to enter the corresponding depressions or recesses e' (of the member 44), when the latter are brought into register with said processes under conditions of excessive speed of the engine, as presently to be described. Under normal conditions, the projections d' simply ride over the faces m' , m' , of the clutch member 44, being limited in one direction by the shoulders r defining one of the terminal limits of the faces m' . On the other hand, the presence of the shoulder or offset r depresses the surface m' on one side of the recess e' below that on the other side of the recess, leaving one wall of the recess higher than the other (see particularly Fig. 5). The higher wall positively insures the passage of the tooth or projection d' into the recess when the member 44 is rocked through a sufficient arc to bring the tooth opposite said recess.

The operation of the mechanism may be best described by a reference to Figs. 5, 7, 13 and 14. The diagrammatic illustration in Fig. 13 shows the superposed position of the several formations on the members 8, 13, 44, as they occur in Fig. 5, and the illustration in Fig. 14 shows their superposition as they occur in Fig. 7. Under normal service conditions, where the load on the engine is practically constant, the speed of the shaft S and the fly-wheel W is governed by the governor G, the balls thereof in rising and falling controlling the valves V, V, through the medium of the reach-rods 15, 15, clutch members 8, 13, (Fig. 5), arm 9, connecting rod 10, cross-head 11, and plunger 12, as well understood in the art. In this series of connections however, the clutch members 8 and 13 I consider novel. Under the normal or service conditions referred to, the operator sets the clutch members 8, 13, 44, as indicated in Fig. 5, that is to say, he causes the projections d of the member 8 to enter the depressions e of the member 13, it being of course necessary to compress the spring 48 for that purpose, whereby the member 13 is locked to the member 8. This brings the ends of the projections d' of the member 13 into engagement with the faces m' of the member 44, thus uncoupling the member 44 from the member 13. As the governor balls rise and fall, the connecting-rod 10 rises and falls and causes a vertical oscillation to be imparted to the arm 9, which, through the medium of the coupled or locked members 13, 8, (the latter being set-screwed to the shaft 6) rocks the shaft 6, thereby oscillating the arms 14, 14, (leading from the member 13) which actuate the reach-rods 15 coupled to the inlet valves V, V. The valves

V, V, are thus controlled directly from the governor under normal service conditions, the projections d' of the member 13 riding over the surfaces m' of the member 44 between the offsets r and the recesses e' (Figs. 5 and 13). Under the normal service conditions referred to, the trigger rods 39, 37, (37'), and yoke 30 are set as indicated to best advantage in Fig. 11, the rod 39 being pushed back toward the governor so as to bring the arm 43 of the clutch ring 44 to substantially the position indicated in Fig. 4. Let us assume now that something happens to the governor belt 4; either that it breaks or slips excessively. If it breaks, the pulley 3 will stop; if it slips excessively, the pulley 3 will lag behind or run very slowly. In either case the governor balls will drop, for the reason that if the belt breaks there is nothing to drive the shaft 2, and if the belt slips excessively, the velocity of rotation of the shaft 2 is materially reduced. With a drop of the governor balls, the arm 9 will be depressed and the arms 14, 14 oscillated in a direction to throw the reach-rods in a direction to open the valve ports to an excessive degree, and thus the engine begins to speed up. Thereupon the fly-wheel will develop sufficient centrifugal force to cause an ejection of the tappet h (Figs. 2, 3, 11,) which when ejected sufficiently, will trip the stem 29 of the yoke 30 upwardly (dotted position Fig. 12) thereby releasing the rod 37 which is forced outwardly from the tube 32 by the action of the spring 35, the rod thus projected causing its rear extension 37' to release the finger a of the trigger-rod 39, which is now projected outwardly from the tube 40 by the expansion of the spring 45, the pull on the rod exerting a pull on the arm 43 to which its opposite end is coupled, the effect of the pull on the arm 43 being to oscillate the latter and impose rotation on the ring or member 44 (of which said arm forms a part) through an arc which is sufficient not only to bring the recesses e' of the member 44 opposite and into engagement with, the projections d' of the member 13, but to turn said ring after the engagement is effected. When the recesses e' are brought opposite the projections d' , the spring 48 forces the member 13 out of locking engagement with the member 8, but drives the member 13 into locking engagement with the member 44, the turn imparted to the ring 44 after the locking thereto of the ring 13, rotating both rings as a unit, thus bringing the projections d of the member 8 opposite the face m of the ring 13 (Figs. 7, 14), over which face the said projections are free to ride. The ring 13 being now free from the ring 8, it follows that any oscillation imparted to the arms 14, 14, can no longer come from any oscillation of the arm 9 coupled to the governor, so that when the members 8, 13

13, are uncoupled as a result of the rocking of the ring 44 by the release of the trigger-rod 39 under the high-speed conditions due to breakage or excessive slippage of the governor belt 4, the governor no longer has control over the members 14, 14, and reach-rods 15, 15, and hence loses control over the valves V, V. So that, under the high speed conditions referred to, the inlet valves are actuated directly by the rod 39 acting under the tension of the spring 45, said spring being effective owing to the release of said rod from the trigger-rod 37, (37') which is in turn released by the tripping of the yoke 30 by the tappet h. When however the arm 43 is oscillated by the release of the trigger-rod 39, the members 13 and 44 are rocked as a unit through an arc sufficient to cause the arms 14, 14, to impart the necessary movement to the reach-rods 15, 15, to cause the latter to rock the inlet valves V, V, to closed position, thus cutting off all supply of steam to the cylinder and bringing the engine to a stop. To reset the parts the operator or engineer disconnects the member 13 from the member 44, by compressing the spring 45, giving the ring 13 a sufficient turn to bring the same into locking engagement with the ring 8, whereupon the parts are restored to the position indicated in Figs. 5 and 11, the broken belt having in the meantime been repaired, or if the undue speed was caused by a slipping belt, the defect having been remedied by shortening the loose belt.

35 It is to be understood that I do not restrict the application of the invention to engines in which the governor is driven by a belt, nor do I restrict the invention to steam engines, as it may be applied to air, gas, electric, or other motor-fluid operated engines.

40 Having described my invention, what I claim is:

1. In combination with a motor-fluid operated engine, a belt driven governor therefor, valves controlled by the governor under normal service conditions, a shaft mounted adjacent to the governor, a clutch-ring mounted loosely on the shaft and normally coupled to the governor and to the valves, a coöperating clutch ring mounted loosely on the shaft, a fly-wheel, a series of spring-controlled trigger-rods interposed between the last named clutch-ring and fly-wheel, and set to normally maintain the last 55 mentioned clutch-ring out of locking engagement with the first ring aforesaid, a compression-spring interposed between the first mentioned clutch-ring and the governor, and a centrifugally operated tappet on 60 the fly-wheel for tripping the trigger-rods with excessive speeds of the engine, the

clutch-rings being provided with suitable formations to effect release of the first ring from the governor and a locking engagement thereof with the last mentioned ring, 65 whereby the governor is disconnected from the valves, and the valve controlling devices are coupled to the last mentioned clutch-ring, the release of the trigger-rods rocking the last clutch-ring through an arc sufficient to effect a cut-off of the motor-fluid to the cylinder.

2. In combination with a motor-fluid operated engine, a belt driven governor, a rock-shaft adjacent the governor, a clutch member secured to said shaft, an arm leading from said member, a governor connecting-rod coupled to said arm, a second clutch member mounted loosely on the shaft and normally locked to the first clutch member, 75 a compression spring interposed between the members, arms leading from the loose clutch member in opposite directions, a cylinder, inlet valves for the cylinder, reach-rods connecting the valves to the arms of the loose 80 clutch member aforesaid, a third clutch member mounted loosely on the rock-shaft adjacent the second mentioned clutch member, an arm carried by the third clutch member, a spring-controlled trigger-rod 90 leading from said arm, a second reciprocating spring-controlled trigger-rod set to normally engage the first rod, a member for holding the last mentioned rod in its set position, an engine-shaft, a fly wheel on the 95 shaft, and a spring-controlled tappet responding to the centrifugal force of the fly-wheel for tripping the member holding the second trigger-rod, whereby both trigger-rods are released, and whereby the second 100 clutch member is unlocked from the first clutch member and locked to the third mentioned clutch member, and whereby the governor releases control of the valves and the latter are directly controlled by the last 105 mentioned pair of interlocked clutch members, the release of the trigger-rods rocking the last interlocked clutch members through an arc sufficient to close the inlet valves.

3. In a device of the character described, 110 a spring-controlled trigger-rod, means for supporting the same, in combination with a swinging tripper yoke normally engaging one end of the rod, and a centrifugally operated tappet for striking the yoke and releasing the rod.

In testimony whereof I affix my signature, in presence of two witnesses.

WARREN H. NUTTER.
